METHOD OF REFINING OILS WITH "VERSENE"

Edward M. James, Winchester, Mass., assignor to
Lever Brothers Company, New York, N. Y., a
corporation of Maine

**No Drawing. Application August 9, 1950,
Serial No. 178,546**

9 Claims. (Cl. 260—425)

1

This invention relates to the refining of vegetable and animal oils, and more particularly to a process of reducing losses experienced when said oils are treated with aqueous alkali solutions to separate free fatty acids therefrom.

The caustic alkali solutions conventionally employed to neutralize the free fatty acids present in fatty glyceride stocks frequently through emulsification or occlusion carry off a portion of refined neutral oil, thereby occasioning considerable losses in large scale commercial processing.

Accordingly, it is an object of the present invention to achieve a reduction in the losses of glyceride oils and fats during alkali-refining.

It is a further object to provide a method of refining such fats and oils by either continuous alkali-refining processes or batch refining processes which is characterized by low refining losses.

These objects are accomplished by incorporating in the refining mixture a small amount of an organic amino-carboxylic acid compound having in relation to one basic nitrogen atom more than one carboxylic acid group standing in alpha position thereto. This compound may be dissolved or dispersed in the oil or in the aqueous alkali solution prior to blending, or it may be added to the oil-aqueous alkali-refining mixture.

Ethylenediaminetetraacetic acid is preferred and has the following formula:

It is available commercially in the form of the tetrasodium salt under the trade-mark "Versene," and may be employed as the acid or as an acidic or neutral salt. While this compound is preferred, any compound of the above-defined type may be employed, such as trimethylamine tricarboxylic acid, and alkyl and aryl iminodiacetic acids in the acid form or as an alkali metal salt such as the sodium, potassium, ammonium or equivalent water-soluble acidic or neutral salt.

Compounds of this type have been found effective, whether employed in the wet or dry batch alkali-refining processes, or in a continuous refining process. Those processes are described in detail in the literature and form no part of the present invention. For convenience in understanding the invention, however, it may be stated that in batch refining a measured amount of oil with a quantity of aqueous alkali slightly in excess of that required to fully neutralize the free fatty acids contained therein are mixed in a kettle

9

and heated. In the dry method the soap stock is allowed to settle at the bottom of the kettle and then recovered in a solid or semisolid form from the cooled oil. In the wet method a spray of hot water is directed upon the surface of the oil, washing down the precipitated soap stock.

1. A continuous method to which the process of the invention is particularly applicable is the Sharples centrifugal process. In this process 10 continuous streams of oil and aqueous alkali are fed and mixed at room temperature, i. e. 75° F., then heated quickly to about 140° F. to break the emulsion of oil and soap stock, and the soap stock and oil separated in high speed centrifuges. 15 The refined oil may be washed once or twice with 10% of its own weight of water at 150° to 180° F., and dried in a vacuum to remove occluded water. The process has been the subject of numerous patents describing variations. The 20 process is equally applicable to these variations.

It has been determined that as little as 0.075% of the additive is sufficient in many cases to markedly reduce refining losses. However, up to 1% can be employed with good results. Surprisingly, between 0.075 and 1% is the optimum range, amounts of additive below the range giving near-normal or even more than normal refining losses, and amounts above it giving no greater reduction therein.

The process of the invention is especially applicable to the alkali-refining of soybean oil, and cottonseed oil. It may be used in the alkali-refining of glyceride stocks composed of vegetable and animal oils of all types, and mixtures thereof, such as corn oil, peanut oil, linseed oil, sesame oil and tung oil, to mention a few of the vegetable oils, and animal oils, such as sardine, herring or menhaden oils. The process is adapted to the refining of either crude or degummed oils.

Any alkali hydroxide may be employed, although sodium hydroxide is most generally used. Also, nonsaponifying alkalis, such as sodium carbonate, or trisodium phosphate, or mixtures thereof with saponifying alkalis may be used.

The maximum amount of alkali as NaOH to be used is calculated from the usual formula:

$$\text{Percent } \frac{\text{f. f. a.}}{5.2} + 0.54 = \text{percent dry sodium hydroxide}$$

50 Whether the additive is incorporated in the crude oil or in the aqueous alkali or blended therewith during or after formation of the refining mixture is largely a matter of choice. The additive of the invention is water-soluble and oil-dispersible. In all instances, however, it is pre-

ferred to add the additive in the form of an aqueous solution thereof.

A preferred procedure is to mix an aqueous solution of tetrasodium salt of ethylenediaminetetraacetic acid with the oil, with the injection of 1% to 2% steam before mixing with aqueous alkali.

The following examples are given in order to facilitate a clear understanding of the invention:

Example 1

A number of wet batch process refinings were made on expeller soy bean oil containing 0.60% free fatty acids using 6.7% (12° Bé.) aqueous alkali solutions containing varying quantities of Versene (tetrasodium salt of ethylenediaminetetraacetic acid). These solutions were prepared by adding sufficient 25% aqueous Versene solution to the aqueous alkali to bring the Versene concentration (based on the weight of the oil) to the amount stated. The following results were obtained:

	Percent refining loss
Control (no Versene)	10.8
1% Versene	2.8
0.5% Versene	3.8
0.1%	3.6

In all cases the sodium hydroxide concentration solution was 6.7% (12° Bé.).

The foots was formed very rapidly in sand-like particles which settled quickly, and on settling packed so tightly that a minimum amount of oil was entrained therein. Wash water applied formed a clean layer between the foots and the oil, being unable to penetrate the tightly packed foots mass. In contrast, the wash water during a refining without the addition of Versene penetrated the foots at the bottom of the kettle. Very clean separations without emulsion formation were obtained when Versene was used as an additive.

In a run without additive the foots were light and flocculent, and the oil retarded the settling of the floc-like particles, whereas in the run containing Versene, the particles were spherical in shape and were not retarded by the oil once they were formed.

Example 2

A 25% solution of Versene (tetrasodium salt of ethylenediaminetetraacetic acid) was added to aqueous sodium hydroxide solutions of varying concentrations. The resulting solutions were used in refining with nondegummed expeller soy bean oil containing 0.60% free fatty acids, using the Sharples continuous method with the injection of 1 1/2% steam as described heretofore. The following results were noted:

	Percent Refining Loss	Percent Refining Efficiency
Control	4.80	97.30
0.05% Versene	5.16	97.43
0.075% Versene	4.77	97.83
0.1% Versene	4.34	98.27

¹ The neutral oil recovered divided by the neutral oil in the unrefined stock expressed in percentage.

The results of the above tests show that ethylenediaminetetraacetic acid is not effective in amounts below about 0.075% by weight.

Example 3

Nondegummed soy bean oil containing 0.6% ⁷⁵

free fatty acids was refined by the Sharples continuous method with aqueous alkali in the presence of Versene (tetrasodium salt of ethylenediaminetetraacetic acid), mixing the components at 75° F. (cold mixing), and with injection of 1 1/2% steam to the oil as described previously. The following results were obtained:

10	Percent Refining Loss	Percent Refining Efficiency
Control (1 1/4% Steam injected, no Versene)	4.79	97.80
Cold Mixing with 0.1% Versene	4.50	98.05
Cold Mixing with 0.125% Versene	4.49	98.06
Cold Mixing with 0.075% Versene	4.66	97.89
1 1/4% Steam plus 0.125% Versene	4.29	98.26
1 1/4% Steam plus 0.1% Versene	4.32	98.23

Example 4

20 Nondegummed soy bean oil containing 0.55% free fatty acids was treated with aqueous alkali in the presence of a tetrasodium salt of ethylenediaminetetraacetic acid in a Sharples continuous refining process with 1 1/2% steam injection, as set forth in Example 2, with the following results:

30	Percent Refining Loss	Percent Reduction in Loss	Percent Refining Efficiency
Control	4.20		97.55
0.10% Versene ¹	3.49	0.71	98.27
Do ²	3.59	0.61	98.17

¹ In this run the Versene was added to the blended mixture.

² In this run the Versene was added to the aqueous alkali.

While specific examples of the invention have been given above, it is to be understood that this has been done merely for purposes of illustration and that the true scope of the invention is not to be considered as limited thereby.

The refined oil is substantially completely neutral and free of residual impurities, is of excellent quality and meets the color requirements of the art. The additives of the invention have no deleterious effects on the normal operation of continuous alkali-refining processes.

Other variations and modifications of the invention will be apparent to those skilled in the art, and the invention contemplates all such variations and modifications which come within the scope of the appended claims.

All amounts and percentages are on a weight basis unless otherwise indicated. Proportions of additive are by weight of the crude oil.

I claim:

1. A process of refining a fatty glyceride stock which comprises treating the stock with aqueous alkali solution in an amount at least sufficient to neutralize free fatty acids contained in the stock, in the presence of not over 1.0% of an organic amino-carboxylic acid compound selected from the group consisting of tetra alkali metal salts of ethylene diamine tetraacetic acid, tri alkali metal salts of trimethylamine tricarboxylic acid and di alkali metal salts of alkyl and aryl iminodiacetic acids to reduce refining losses, and then separating soapstock from the refined oil.

2. A process in accordance with claim 1 wherein the soapstock and refined oil are separated centrifugally.

3. A process of claim 2 in which the stock and alkali are continuously mixed and in which the centrifugal separation is carried out continuously.

4. A process of claim 1 in which the soapstock

and refined oil are formed into separate layers by settling.

5. The process of claim 1 wherein the fatty glyceride is a soy bean oil.

6. A process of claim 1 wherein the organic amino-carboxylic acid compound is the tetra-sodium salt of ethylenediaminetetraacetic acid.

7. The process of claim 3 in which the additive is mixed with oil before mixing with the alkali.

8. The process of claim 7 in which up to 2% of 10 steam is mixed with the oil before mixing with the alkali.

9. A process of claim 1 wherein the organic amino-carboxylic acid compound is a trisodium salt of trimethylamine tricarboxylic acid.

EDWARD M. JAMES.
